WILLIAM J. GAGNON, OF BRIDGEPORT, CONNECTICUT, ASSIGNOR TO THE BEAD CHAIN MANUFACTURING COMPANY, OF BRIDGEPORT, CONNECTICUT, A CORPORATION OF CONNECTICUT

CONTACT OF THE PIN TYPE

Application filed September 14, 1925. Serial No. 56,292.

My invention relates to pin type contacts, and particularly to contacts for circuit extension appliances such as lamps, audions, attachment plugs, etc. The object of my invention is to provide a sheet metal tubular contact which possesses a rigidity comparable to that of the usual contact pin formed from rod or bar stock, and has the technical advantages of the pin described in my copending application, filed herewith. My present invention provides a modified form of pin adapted to be molded in to its associated base.

In the accompanying drawing, in which all the views show pins drawn to a scale considerably enlarged over its usual commercial form—

- Fig. 1 is a side elevation of a pin alone;
- Fig. 2 is a section on the line 2—2, Fig. 1;
- Fig. 3 is a top plan view of an audion base to which my invention is applied; and
- Fig. 4 is a section on the line 4—4, Fig. 3.

The present contact, like that disclosed in my application of even date, is formed from sheet metal, and its general characteristics and advantages are the same as compared with contacts formed from bar or rod stock. Briefly, it comprises a tubular shank 5, the contact end of which is preferably reduced as at 6 to accommodate the solder drop 7 by which the threaded through lead wire 8 is engaged and electrically connected to the contact end.

Where the material of the base 9 permits, it constitutes an economy of manufacture to mold the contact in position when the base is formed. For the sake of explanation it may be assumed that the base 9 is of glass, which, when it can be used, not only affords excellent insulation, but involves considerable economy of material over such relatively expensive moldable materials as certain phenol condensation products.

The adaptation of my sheet metal contact of such construction, involves (1) the formation of an anchor head thereon which may be embedded in the material of the base to firmly hold the contact pin in position; (2) the shaping of this head to facilitate the automatic feed of the pins to the molding machine; (3) the formation of the head in such

fashion that the base material is obstructed from entering the interior of the pin during the molding operation; (4) the shaping of the obstructing surfaces at this end in such fashion that the base material, such as glass, readily displaces from the wire entrance mouth at the head of the pin during the formation of the guideway leading thereto through the material of the base itself.

To this end the anchor head of the pin comprises an annular flange 10 adjacent the terminal non-circular area 11, the marginal wall of which is smoothly introverted to form a re-entrant conical mouth 12 with rounded surfaces. The flange 10 forms not only an anchor against longitudinal displacement of the pin in the base, but also as a support for the pin as it moves along its feed guide at the molding machine. The embedded polygonal area of the head prevents swivelling of the pin in the base.

The re-entrant conical mouth 12 serves the important function of barring the more or less fluid or plastic hot glass, or the like, from the interior of the pin when the base material is introduced into the mold in which the heads of the pins are already positioned. Moreover I have found that the rounded surfaces of the cone cooperate with the former 13 as the latter descends to shape the guideways 14 in the base, so that such base material as initially enters the cone, flows or is pressed out as the former enters. Should some of the base material be carried into the pin with the stem 15 of the former, the interior of the bulbous head of the pin affords such ample space to accommodate such material that no blocking of the wire way can possibly occur.

The periphery of the base is generally channelled at 16 to receive an inwardly offset bead 17 on the metal shell 18, but this feature and the general construction of the base do not enter into my invention. While I have shown a construction which is efficient and economical to manufacture and assemble, various other contours and constructions which accomplish my invention will readily occur to those dealing with the problem. Moreover, while I have shown a pin associ-

- ated with the base of an audion, its utility in other electrical fittings will be obvious, while in fittings such that electrical connection is effected otherwise than by threading through a lead wire to the contact end of the pin, such modifications in construction as adapt it to such conditions will readily occur to those skilled in the art.
- With the understanding therefore that the construction shown is but an illustrative embodiment of the conception which underlies my invention, I claim—
1. A longitudinally split pin formed from sheet metal stock and laterally closed throughout its length, and comprising a bulbous head at one end, and a rigid tubular shank extending therefrom.
  2. A longitudinally split pin formed from sheet metal stock and laterally closed throughout its length, and comprising a bulbous head at one end, and a rigid tubular shank extending therefrom, the head end of the pin having an integral transverse closure element affording a restricted opening for the entry of a lead wire.
  3. A longitudinally split pin formed from sheet metal stock and laterally closed throughout its length, and comprising a bulbous head at one end, and a rigid tubular shank extending therefrom, the end of the shank having an integral closure affording a restricted opening for the exit of a lead wire.
  4. A longitudinally split pin formed from sheet metal stock and laterally closed throughout its length, and comprising a bulbous head at one end, and a rigid tubular shank extending therefrom, the opposite ends of the pin having integral closures affording restricted wire openings.
  5. A rigid tubular contact pin formed from sheet metal stock and having a transverse diaphragm at an end thereof.
  6. A rigid tubular contact pin formed from sheet metal stock and having a peripheral anchorage shoulder adjacent one end, said end being obstructed by a transverse diaphragm.
  7. A rigid tubular contact pin formed from sheet metal stock and having a head end adapted to be molded into an insulating base, said end having a transverse diaphragm which serves, during the molding operation, to exclude the moldable material of the base from the interior of the pin.
  8. A rigid tubular contact pin formed from sheet metal stock, in combination with a molded insulating base to which one end of the pin is rigidly attached, said end of the pin having a mechanical engagement with the base to prevent longitudinal and rotary displacement with respect thereto and affording a guide mouth for the entry of a lead wire to the interior of the pin.
  9. A rigid tubular contact pin formed from sheet metal stock, in combination with a molded insulating base to which one end of the pin
- is rigidly attached, said end of the pin having a head and an annular shoulder cooperating with the base to prevent relative movement of the parts, and the base and pin end being apertured in register to admit a lead wire to the interior of the pin.
10. A tubular contact pin for the base of a radio tube, having a securing head to be embedded in the base, said head having an introverted cross web for formation of a wire way to the interior of the pin.
11. A radio tube having a base with tubular contact pins with their heads molded therein, the heads of said contact pins having introverted cross webs, as and for the purpose set forth.
- In testimony whereof I have signed my name to this specification.
